DESIGN FOR A DISPENSER FOR PAPER NAPKINS

Frank L. Broeren, Neenah, and Samuel N. Hope, Wauwatosa, Wis., assignors to Marathon Paper Mills Company, Rothschild, Wis., a corporation of Wisconsin

Application December 20, 1937, Serial No. 73,746

Term of patent 14 years

To all whom it may concern:

Be it known that Frank L. Broeren and Samuel N. Hope, citizens of the United States, residing, respectively, at Neenah, Winnebago County, and Wauwatosa, Milwaukee County, in the State of Wisconsin, have invented a new, original, and ornamental Design for a Dispenser for Paper Napkins, of which the following is a specification, reference being had to the accompanying drawing, forming a part thereof.

We claim:

The ornamental design for a dispenser for paper napkins, as shown.
